UNITED STATES PATENT OFFICE.

CARLETON RUHE, OF NEW YORK, N. Y.

LEATHER-POLISHING MACHINE.

1,419,522.

Specification of Letters Patent. Patented June 13, 1922.

Application filed February 27, 1920. Serial No. 361,623.

To all whom it may concern:

Be it known that I, CARLETON RUHE, a citizen of the United States, residing in the city, county, and State of New York, have 5 invented certain new and useful Improvements in Leather-Polishing Machines, of which the following is a specification.

My invention relates to a machine for brushing leather and more particularly to a 10 leather polishing machine for polishing or finishing sole leathers in one operation such as sides, backs, bends, bellies, and also harness leather. My invention is an improvement of my prior patent Reissue No. 13,984, 15 reissued September 21, 1915.

One of the objects of my invention is to provide a rotary brush leather polishing machine with a vertically movable flat platform in combination with a conveyor for the 20 leather running over the platform whereby leather may be presented flat to the brushes of the machine and be supported at all points while passing between and under the brushes and through the machine at the same 25 time providing means for raising the platform so as to subject the leather while being polished to the high pressure necessary for producing a correct finish.

Another object of my invention is to provide 30 a flat bed for the conveyor which may be raised uniformly and simultaneously at all points by means of a system of screws connected by a chain and sprocket, the heavy thrust to which the platform is subjected 35 during the polishing action being taken up by ball bearings. Despite the heavy pressure of the brushes the platform is easily moved up and down by means of a hand-wheel.

40 My invention consists more especially in the parts, improvements and combinations herein described, and more particularly pointed out in the claims.

Referring now to the accompanying drawings forming a part of the specification, Fig. 45 1 is a side elevation of my improved rotary brush polishing machine with a part broken away.

Fig. 2 is a sectional detail showing part 50 of the mechanism for raising the platform.

Fig. 3 is a detail view of the gearing for connecting the supports for the platform so that they may be raised simultaneously.

The sides 1 of the metal frame of the 55 machine are connected by tie-bars 2 so as to provide a firm foundation. A plurality of

rotary brushes 3, 4, 5 are carried by the frame and extend crosswise thereof. The shafts 6, 7 and 8 of the brushes are parallel and are arranged in bearings adapted to 60 oscillate slightly. These bearings include a collar 9 mounted to oscillate slightly on screws 10, the said screws in turn being carried by yoke 11 to which is secured a pivot pin 12 free to turn in socket 13. One of these 65 bearings is mounted at each end of brush shaft 6, 7 and 8. The ends of the shaft are thus pivotally supported so that they may readily align themselves. Gearing is provided for connecting the brushes, the brushes 70 being driven from a pulley (not shown) on the far end of shaft 7 of brush 4. The brushes are rotated at a higher speed than the conveyor driving shaft and all of the brushes are rotated in the same direction. 75 The intermediate brush 7 is driven at a greater rate of speed than the outer brushes. The conveyor driving shaft carries at one end the gear 15 which in turn meshes with the reduction gear 16 on shaft 17, the opposite end of the shaft 17 carrying gear 18 80 which is driven by the belt 20. The belt 20 passes around the reducing pulley 21 upon the shaft of the brush 8, the said shaft also carrying the sprocket gear 22 around which 85 passes the chain 23 which in turn engages the sprocket 24 on the power shaft 7. A sprocket chain 25 and a sprocket 26 connect shaft 7 of brush 4 with the shaft 6 of brush 3. This system of brushes and the driving 90 mechanism therefor as well as the bearings for the brushes are substantially the same as those of my prior Patent No. 1,213,908 of January 30, 1917. A conveyor in the form of an endless conveying apron 27 extends 95 beneath the brushes for receiving the leather to be polished. This conveying apron which is preferably a rubber-covered belt, is driven from the power shaft 7 and runs around the rollers 28 and 29 at opposite ends of the machine, said rollers being carried by swinging arms 30, 31 and the conveyor being tightened by means of set screws 32 and 33. The speed of the conveyor which feeds the leather through the machine is much less than the 100 surface speed of the brushes.

Coming now to the leading feature of my invention, I provide in combination with the conveyor and brushes a flat platform extending from the brush at the feeding end 110 of the machine, at the left of Fig. 1, to the brush at the delivery end of the machine, at

- the right of Fig. 1. This platform lies between the side frames of the machine and within the conveyor and provides a firm level support for the upper portion thereof.
- 5 It is mounted independently of the conveyor. Means for raising and lowering all portions of the platform uniformly are provided. A plurality of vertically adjustable posts, one at each corner of the platform, 10 is utilized. The platform is detachably secured to these posts by means of brackets 34 secured to the platform, the posts being provided with projections 35 passing into the apertures of the brackets. A drift pin 36 detachably secures the posts to the brackets and prevents rotation of the posts. The posts carry screw thread portions 37 which are in turn engaged by screw thread sleeves 38, the sleeves 38 being carried by 15 the fixed frame. By turning the sleeves 38, the screws 37 and the platform are raised or lowered, the platform moving with respect to the brushes and the conveyor. Gearing is provided so that upon turning one screw 20 threaded sleeve all of the screw threaded posts are uniformly raised and lowered, the gearing actuating the sleeves. As illustrated, I make use of sprockets 39, 40, 41, 42, each sprocket being secured to the corresponding sleeve. A sprocket chain 43 connects the sprockets so as to give the movement to the screw threaded sleeves. Owing 25 to the pressure to which the bed is subjected and the desirability that it may not bind 30 or stick at any corner and to provide an easily operated mechanism I make use of thrust ball bearings 44, the balls of which run between plates 45. One of the plates 45 is secured to the frame of the machine 35 and the other is attached to the screw threaded sleeve. A hand-wheel 46 is secured to one of the sleeves 38, thus providing a manually operated means for actuating 40 the raising mechanism of the platform.
- 45 To secure compactness of the machine and ease of access to the raising mechanism for the platform I mount the posts which support the platform and the sleeves for actuating them in inwardly projecting brackets 47. 50 These brackets are preferably integrally connected with the side frames of the machine, are mounted between the upper and lower reaches of the conveyor belt, and are located beneath the end brushes. In this 55 way the brackets for the platform and the raising and lowering mechanism are arranged directly beneath the platform, between the frames of the machine and in the upper portion thereof, provide a rigid support for the table, and the mechanism can be easily inspected and is accessible and repaired if necessary by merely removing the conveyor belt or by getting under the machine.
- 60 65 The platform preferably comprises cross
- pieces 48 secured to the side braces 49, a series of longitudinal strips 50 being laid upon and carried by the cross braces so as to make a flat, level table-top.
- Having thus described the invention the 70 operation will be clear. The machine is driven by power and a piece of leather is laid upon the conveying belt at the left hand side of the machine in Fig. 1, and is carried through the machine at a uniform speed 75 over the flat table-top and under the rotatable brushes. The table-top has been previously adjusted so as to give the desired polishing pressure between the leather and the brushes. The leather whose grained side 80 has preferably been treated with a compound is kept flat in its passage through the machine because of the flat platform over which the conveyor rides, the polishing action over the entire surface of the leather is 85 uniform and a glossy, uniform finish results. The table gives a uniform pressure against each brush from end to end and the same pressure against all the brushes. The leather cannot sag as it passes through the 90 machine nor bind, and is completely supported at all points. The bed may be easily raised and lowered when desired to vary the pressure according to the character of the stock to be finished. The platform is moved 95 transversely of the conveyor, the conveyor passing around rollers carried by the frame of the machine and the platform being mounted independently of the conveyor.
- It will be understood that the structure 100 thus hereinbefore specifically described may be varied in a great number of details, and that certain features thereof may be used in the absence of others without departing from the spirit of the invention and such 105 changes in detail of construction and such uses of some in the absence of others, are intended to be within the scope of the claims hereto appended.
- Having described my invention, what I 110 claim is:
1. In a leather polishing machine the combination of a frame, a flat platform mounted between the sides of the frame independently of the conveyor, an endless 115 conveyor passing above said platform and returning beneath the same, thus forming a flat work support for the leather to be polished, said conveyor carried by rollers mounted in the frame of the machine, a 120 plurality of rotary brushes carried by said frame above said conveyor, means for driving said conveyor at a lower speed than that of the brushes and means for raising and lowering said platform with respect to said 125 brushes and conveyor.
  2. In a leather polishing machine the combination of a frame, a flat platform mounted between the sides of the frame, an endless conveyor passing above said platform and 130

- returning beneath the same, thus forming a flat work support for the leather to be polished, rollers mounted on the frame of the machine around which the conveyor travels, 5 said conveyor being thereby mounted independently of the platform, a plurality of rotary brushes carried by said frame above said conveyor, gearing for driving the outer rotary brushes at a lower speed than that of the intermediate brush, means for driving said conveyor at a lower speed than that of the brushes, a plurality of supports for the platform, mechanism for connecting said supports so that the platform may be raised 10 uniformly and manually operated means for actuating said raising mechanism.
3. In a leather polishing machine the combination of a frame, three rotatable brushes extending crosswise of the frame, gearing 20 connecting said brushes, a power shaft for driving said brushes, all of said brushes rotating in the same direction and the intermediate brush being driven at a greater speed than the outer brushes, an endless conveying apron extending beneath the brushes 25 for receiving the leather to be polished, said conveying apron being driven from the power shaft at a lower speed than the brushes, a flat platform lying within the conveyor and supporting the upper portion thereof, said platform extending from the brush at the feeding end of the machine to the brush at the delivery end of the machine, a plurality of vertically adjustable posts, 30 one at each corner of the platform, connecting gearing whereby said posts are raised and lowered so as to uniformly move the platform and a hand-wheel for operating said gearing.
4. In a leather polishing machine the combination of a frame, three rotatable brushes extending crosswise of the frame, gearing 40 connecting said brushes, a power shaft for driving said brushes, all of the brushes rotating in the same direction and the intermediate brush being driven at a greater rate of speed than the outer brushes, an endless conveying apron extending beneath the brushes for receiving the leather to be polished, 45 said conveying apron being driven from the power shaft at a lower speed than the brushes, a flat platform lying within the conveyor and supporting the upper portion thereof, said platform extending from the brush at the feeding end of the machine to the brush at the delivery end of the machine, a plurality of vertically adjustable posts, one at each corner of the platform, 50 an endless chain for connecting said posts whereby they are raised and lowered so as to uniformly raise and lower the platform and a hand-wheel for operating said endless chain.
5. In a leather polishing machine the combination of a frame, rotatable brushes extending crosswise of the frame, gearing connecting said brushes, a power shaft for driving said brushes, all of the brushes rotating in the same direction and the intermediate brush being driven at a greater rate 55 of speed than the outer brushes, an endless conveying apron extending beneath the brushes for receiving the leather to be polished, said conveying apron being driven from the power shaft, a flat platform lying within the conveyor and supporting the upper portion thereof, said platform extending from the brush at the feeding end of the machine to the brush at the delivery end of the machine, a plurality of vertically 60 adjustable screws, one at each corner of the platform, a plurality of threaded sleeves, one for each screw carried by the frame, gearing for connecting said sleeves whereby the screws are raised and lowered so as to uniformly raise and lower the platform and a hand-wheel for operating said gearing.
6. In a leather polishing machine the combination of a frame, three rotatable brushes extending crosswise of the frame, gearing 65 connecting said brushes, a power shaft for driving said brushes, all of the brushes rotating in the same direction and the intermediate brush being driven at a greater rate of speed than the outer brushes, an endless conveying apron extending beneath the brushes for receiving the leather to be polished, 70 said conveying apron being driven from the power shaft at a lower speed than the brushes, a flat platform lying within the conveyor and supporting the upper portion thereof, said platform extending from the brush at the feeding end of the machine to the brush at the delivery end of the machine, a plurality of vertically adjustable screws, one at each corner of the platform, a plurality of threaded sleeves, one for each screw carried by the frame, ball bearings between each of 75 said sleeves and the frame, gearing for connecting said sleeves whereby the screws are raised and lowered so as to raise and lower all portions of the platform uniformly and a hand-wheel for operating said gearing. 90
7. In a leather polishing machine the combination of a frame, three rotatable brushes extending crosswise of the frame, gearing connecting said brushes, a power shaft for driving said brushes, all of the brushes rotating in the same direction and the intermediate brush being driven at a greater rate of speed than the outer brushes, an endless conveying apron extending beneath the brushes for receiving the leather to be polished, 95 said conveying apron being driven from the power shaft, a flat platform lying within the conveying apron and supporting the upper portion thereof, said platform extending from the brush at the feeding end of the machine to the brush at the delivery end of the machine, a plurality of vertically adjustable posts, one at each corner of the platform, an endless chain for connecting said posts whereby they are raised and lowered so as to uniformly raise and lower the platform and a hand-wheel for operating said endless chain. 100
8. In a leather polishing machine the combination of a frame, rotatable brushes extending crosswise of the frame, gearing connecting said brushes, a power shaft for driving said brushes, all of the brushes rotating in the same direction and the intermediate brush being driven at a greater rate 105 of speed than the outer brushes, an endless conveying apron extending beneath the brushes for receiving the leather to be polished, said conveying apron being driven from the power shaft, a flat platform lying within the conveyor and supporting the upper portion thereof, said platform extending from the brush at the feeding end of the machine to the brush at the delivery end of the machine, a plurality of vertically adjustable screws, one at each corner of the platform, a plurality of threaded sleeves, one for each screw carried by the frame, gearing for connecting said sleeves whereby the screws are raised and lowered so as to uniformly raise and lower the platform and a hand-wheel for operating said gearing. 110
9. In a leather polishing machine the combination of a frame, rotatable brushes extending crosswise of the frame, gearing connecting said brushes, a power shaft for driving said brushes, all of the brushes rotating in the same direction and the intermediate brush being driven at a greater rate 115 of speed than the outer brushes, an endless conveying apron extending beneath the brushes for receiving the leather to be polished, said conveying apron being driven from the power shaft, a flat platform lying within the conveyor and supporting the upper portion thereof, said platform extending from the brush at the feeding end of the machine to the brush at the delivery end of the machine, a plurality of vertically adjustable screws, one at each corner of the platform, a plurality of threaded sleeves, one for each screw carried by the frame, gearing for connecting said sleeves whereby the screws are raised and lowered so as to uniformly raise and lower the platform and a hand-wheel for operating said gearing. 120
10. In a leather polishing machine the combination of a frame, rotatable brushes extending crosswise of the frame, gearing connecting said brushes, a power shaft for driving said brushes, all of the brushes rotating in the same direction and the intermediate brush being driven at a greater rate 125 of speed than the outer brushes, an endless conveying apron extending beneath the brushes for receiving the leather to be polished, said conveying apron being driven from the power shaft, a flat platform lying within the conveyor and supporting the upper portion thereof, said platform extending from the brush at the feeding end of the machine to the brush at the delivery end of the machine, a plurality of vertically 130 adjustable screws, one at each corner of the platform, a plurality of threaded sleeves, one for each screw carried by the frame, gearing for connecting said sleeves whereby the screws are raised and lowered so as to uniformly raise and lower the platform and a hand-wheel for operating said gearing.

- adjustable screws, one at each corner of the platform, a plurality of threaded sleeves, one for each screw carried by the frame, ball bearings between each of said sleeves and 5 the frame, an endless chain for connecting said sleeves whereby the screws are raised and lowered so as to uniformly raise and lower the platform, and a hand-wheel for operating said gearing.
- 10 8. In a leather polishing machine the combination of a frame, rotatable brushes extending crosswise of the frame, gearing connecting said brushes, a power shaft for driving said brushes, all of the brushes 15 rotating in the same direction and the intermediate brush being driven at a greater rate of speed than the outer brushes, an endless conveying apron extending beneath the brushes for receiving the leather to be polished, said conveying apron being driven from the power shaft, a flat platform lying within the conveying apron and supporting the upper portion thereof, said platform extending from the brush at the feeding end 20 of the machine to the brush at the delivery end of the machine, a plurality of vertically adjustable posts, one at each corner of the platform, said platform being removably secured to said posts, gearing for connecting 25 said posts so as to uniformly raise and lower all portions of said platform, and a hand-wheel for operating said gearing.
9. In a leather polishing machine the combination of a frame, three rotatable 30 brushes extending crosswise of the frame, belts connecting said brushes, a power shaft for driving said brushes, all of the brushes being rotated in the same direction and the intermediate brush being driven at a greater 35 rate of speed than the outer brushes, an endless conveying apron extending beneath the brushes for receiving the leather to be polished, said conveying apron being driven from the power shaft, a flat platform lying 40 within the conveying apron and supporting the upper portion thereof, said platform extending from the brush at the feeding end of the machine to the brush at the delivery end of the machine, a plurality of vertically 45 adjustable posts, one at each corner of the platform, gearing for connecting said posts whereby they are raised and lowered so as to uniformly raise and lower all portions 50 of said platform, and a hand-wheel for operating said gearing.
10. In a leather polishing machine the combination of a frame, a power shaft, a convex roller at one end of the machine, a roller at the other end of the machine, an endless 55 conveyor passing about said rollers and driven from the power shaft, a plurality of 60 rotary brushes for polishing the leather, said brushes comprising two end brushes and an intermediate brush, the axes of the brushes being parallel and extending above and adjacent to the conveyor, multiplying gearing including belts connecting said brushes with the power shaft for driving said brushes at a higher rate of speed than and in the same direction as the conveyor, the multiplying 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 899
